UNITED STATES PATENT OFFICE

CARL E. METHUDY, OF ST. LOUIS, MISSOURI, ASSIGNOR TO METHUDY AUTOMATIC LIGHTER CO., OF EAST ST. LOUIS, ILLINOIS, A CORPORATION OF ILLINOIS

IGNITION DEVICE FOR GAS BURNERS

Application filed November 11, 1929. Serial No. 406,219.

This invention relates to an ignition device for burners of gas stoves.

An object of this invention is to provide an automatic ignition device for a gas stove burner which is simple, economical and safe.

Other and particular objects will appear from the detailed description which follows taken in connection with the accompanying drawings, in which—

10 Fig. 1 is a plan view of the burner, its connections, the ignition device, and its connections.

Fig. 2 is a cross-sectional view taken on line 2—2 of Fig. 1.

15 Gas is supplied through a manifold 1 by a valve 2 through an air mixer 3 to the burner 4. The burner may be of any ordinary construction having holes 5 in its top wall and may comprise a plurality of arms, as specifically illustrated in the drawings.

20 One of the arms is elongated, as shown at 6, to form a connection with the interior of a pilot housing 7 in which constantly burns a lighted pilot jet 8 supplied with fuel through the pipe 9 from the manifold 1.

25 The pilot housing 7 has one or more horizontal outlets 10 to connect with one or more burner extensions 6. An annular baffle plate 11 is situated above the pilot jet 8 and below the outlets 10. Air is admitted to the pilot jet to form a combustible mixture through a suitable orifice at the bottom of the housing shown at 12.

30 The burner extension 6 is connected to the pilot housing 7 by telescoping its end into a suitable female portion in the housing. The burner extension 6 is provided with holes 13 in its top wall of smaller dimension than the regular burner holes 5. Its end wall is closed except for a horizontal opening 14 directed toward the pilot housing 7 and crossing a vertical orifice 15 between the end wall of the extension 6 and the pilot housing 7.

35 The pilot jet 8 is kept burning continuously. When it is desired to light the burner

4, the valve 2 is opened, the gas is mixed with air in the air mixer 3, producing a combustible mixture which flows into and fills the interior of the burner 4, including the extension 6, through the hole 14 in the extension, 50 and into the pilot housing 7 where it comes into contact with the flame from the pilot jet. Combustion occurs, the flame running back to the hole 14 in the end wall, upward through the vertical orifice 15, igniting the 55 mixed gases coming through the holes 13 in the extension, and thence over the entire top surface of the burner. As soon as this has occurred, the gas will be consumed to such an extent that no appreciable amount escapes 60 through the hole 14, and what little does pass through that hole is consumed by a flame which passes upwardly through the vertical orifice 15. The pilot light resumes its normal condition and the pilot housing is otherwise 65 free from flame.

70 While as shown, the pilot housing is connected to only one burner, it will be obvious that it may be connected to as many as desired, ordinarily four.

75 From the foregoing, it will be apparent that an ignition device has been provided which is automatic, simple of construction, and safe and efficient in operation.

Various changes may be made in the details of construction within the scope of the appended claims without departing from the spirit of the invention.

I claim:

1. In combination with a gas burner 80 adapted to receive a combustible mixture, means for igniting the same comprising a pilot jet, a housing therefor, an extension of the burner having a series of spaced holes through its wall, and a member connecting said extension and housing and having an orifice positioned and adapted to permit the escape of flame to ignite the combustible mixture after passing through said holes.

2. In combination with a gas burner 90

adapted to receive a combustible mixture, means for igniting the same comprising a pilot jet, a housing for said jet, an extension of the burner having a series of spaced holes 5 through its wall, and a connecting element between said housing and said extension communicating with the burner through a hole in the end wall of the extension and having a lateral orifice in communication with said 10 hole.

3. A gas burner having an extension with a series of spaced holes through its wall, a pilot jet, a housing for said jet, an element connecting said extension and said housing 15 and having a lateral orifice positioned and adapted to permit the communication of flame therefrom to the extension at said holes.

4. In combination with a gas burner 20 adapted to receive a combustible mixture, means for igniting the same comprising a pilot jet, a housing for said jet, an extension on the burner having a series of spaced minor holes through its wall, and a connecting element 25 between said housing and said extension communicating with the burner through a constricted opening in the end wall of the extension and having a lateral orifice in communication with said opening.

30 5. In combination with a gas burner adapted to receive a combustible mixture, means for igniting the same including a pilot jet, a housing therefor, an extension of the burner having a series of spaced holes 35 through its wall, and a connecting element integral with the extension, the end of said element telescoping into a suitable female portion in the housing.

6. In combination with a gas burner 40 adapted to receive a combustible mixture, means for igniting the same comprising a pilot jet, a housing enclosing said pilot jet, an extension of the burner having a series of spaced holes through its upper wall and 45 having an end wall provided with a hole therethrough, and means including said hole in said end wall forming a communication from said extension to said housing.

7. In combination with a gas burner 50 adapted to receive a combustible mixture, means for igniting said mixture comprising a pilot jet, a housing enclosing said jet and having an orifice in its lower end for admitting air into the housing, an extension of the 55 burner having a series of spaced holes through its upper wall and having an end wall provided with a hole therethrough, and a member connecting said extension and said housing and having an orifice positioned and 60 adapted to permit the escape of flame to ignite the combustible mixture after said mixture passes through said first named holes in said burner.

8. In combination with a gas burner 65 adapted to receive a combustible mixture.

means for igniting said mixture comprising a pilot jet, a housing for said jet, a hollow extension of the burner having a series of spaced holes through its upper wall and a 70 hole through its end wall, and a tubular connecting element between said housing and said extension receiving gas from said hole in said end wall of said extension and having an orifice located and adapted to permit the escape of flame to ignite the combustible 75 mixture after said mixture passes through said first named holes in said extension.
